UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

DESIGN FOR A FIREBACK OR SIMILAR ARTICLE.

Application filed July 27, 1923. Serial No. 6,876. Term of patent 7 years.

To all whom it may concern:

Be it known that I, GEORGE E. PICKUP, a citizen of the United States, residing at Newark, in the county of Licking and State of Ohio, have invented a new, original, and ornamental Design for Fireback or Similar Article, of which the following is a specification, reference being had to the accompanying drawings, forming part thereof.

The figure is a front elevational view of a fireback or similar article, showing my new design.

I claim:

The ornamental design for a fireback or similar article, substantially as shown.

GEORGE E. PICKUP.
